United States Patent Office

Des. 178,172
Patented July 3, 1956

178,172

SCREEN DOOR GRILLE

Walter A. Curtze, Erie, Pa.

Application October 3, 1955, Serial No. 38,194

Term of patent 14 years

(Cl. D54—2)

Fig. 1

Fig. 2

Fig. 1 is a front elevational view of the screen door grille showing my new design; and

Fig. 2 is a top edge view.

I claim:

The ornamental design for a screen door grille, substantially as shown.
